Patented May 10, 1921.

UNITED STATES PATENT OFFICE.

GEORGE R. THURMAN, OF ST. LOUIS, MISSOURI, ASSIGNOR OF ONE-HALF TO SHIRLEY D. GREGSON, OF ST. LOUIS, MISSOURI.

BUCKLE.

1,377,233.

Specification of Letters Patent. Patented May 10, 1921.

Application filed February 11, 1921. Serial No. 444,163.

To all whom it may concern:

Be it known that I, GEORGE R. THURMAN, a citizen of the United States of America, and a resident of the city of St. Louis, in the State of Missouri, have invented certain new and useful Improvements in Buckles, of which the following is a full, clear, and exact description, reference being had to the accompanying drawings, forming a part of 10 this specification.

This invention relates to improvements in buckles, and more particularly to a buckle adapted to form part of a tie for holding a lid on a receptacle, and provided with a tag-15 attaching device whereby an ordinary shipping tag can be easily and quickly secured to and removed from the tie.

When a number of small articles are purchased from a retail store, such as a department store, these articles are usually packed 20 in a box provided with a tie in the form of a strap and buckle which surrounds the box to secure the lid thereon. According to the ordinary practice, the address of the pur-25 chaser together with a list of the articles in the box are usually written on a separate sheet of paper which is pasted onto the shipping tag, and a string is used to tie the tag to the strap which surrounds the box. After 30 the goods have been delivered, the shipping tag is usually torn from the string, this being the most convenient manner of removing the tag. Considerable time and labor is involved in using short individual pieces of 35 string to secure shipping tags to the straps, it being necessary to insert each string through the eye of a tag and to then tie the string around the strap. These operations are repeated hundreds of times every day in 40 the packing room of the average department store.

I propose to entirely eliminate the cost of the string, as well as the time and labor ordinarily involved in tying the tags to the 45 straps.

With the foregoing and other objects in view, the invention comprises the novel construction, combination and arrangement of parts hereinafter more specifically described 50 and illustrated in the accompanying drawings wherein is shown the preferred embodiment of the invention. However, it is to be understood that the invention comprehends changes, variations and modifications which

come within the scope of the claims hereunto 55 appended.

Briefly stated, the device about to be described is a tie comprising a strap adapted to pass around a box, and a tag-attaching device whereby a shipping tag can be very 60 easily and quickly attached to the tie. The tie includes a buckle connecting the ends of the strap, and the tag-attaching device is preferably in the form of a clip extending from one side of the buckle, so as to lie 65 entirely beyond the strap-securing means in the buckle. Instead of cutting a piece of string from a source of supply and passing the same through the eye of a tag and tying it around the strap, it is only necessary to 70 apply the tag to the clip on the buckle, and this can be done in a few seconds' time. Furthermore, the tag can be quickly removed 75 from the clip without in any way mutilating the tag, so it can be conveniently reused after a new address sheet has been pasted onto the same.

Figure I is a perspective view illustrating a tie passing around a box, and showing a buckle provided with a tag-attaching device. 80

Fig. II is an enlarged fragmentary top view, partly in section, showing a buckle connecting the ends of a strap, and also showing the tag-attaching device at one side of the buckle. 85

Fig. III is an end view of the buckle shown in Fig. II.

Fig. IV is a side elevation of the buckle.

A designates a box provided with a lid B, and C is a strap surrounding the box and 90 its lid. The ends of the strap are connected together through the medium of a buckle.

The buckle herein shown includes a rigid frame consisting of side members 1 formed integral with end members 2 and 3, and also integrally connected to intermediate transverse members 4 and 5. One end of the strap C is secured to the buckle member 3, while the other end is inserted between the buckle members 2 and 4 and detachably secured by means of a gripping tongue 6 pivotally mounted on the member 5 and provided with a toothed edge 7 (Fig. II) which cooperates with the member 2 to secure 95 the strap. 100

The tag-attaching clip herein shown comprises a keeper in the form of an eye, or hook, 8 extending outwardly from one of

the side members 1 and provided with an end 8' (Fig. III) adapted to pass through the eye of a tag T. The clip also includes a yielding spring tongue 9 located at one side 5 of the buckle and adapted to engage the end 8' of the eye 8, so as to secure the tag. One end of the tongue 9 is rigidly secured to a lug 10 extending from one side of the buckle, and its opposite end portion yieldingly en- 10 gages the end 8' of the hook, or eye 8.

The tag-attaching clip is thus secured to one side of the buckle, where it will not in any way interfere with the strap-securing means between the side members 1 of the 15 buckle. The tag can be easily and quickly applied to and removed from the eye 8, but when the tag is attached as shown in Figs. I and II it is securely held and it is not liable to be accidentally removed from the 20 buckle.

I claim:

1. A buckle provided with a tag-attaching device adapted to receive the eye of a shipping tag.
- 25 2. A buckle comprising a frame provided with side members, strap-securing means between said side members, and a tag-attaching clip comprising a keeper secured to and extending from one of said side mem- bers.
- 30 3. A buckle comprising a frame having side members, strap-securing means between said side members, and a tag-attaching clip

comprising a keeper extending outwardly from one of said side members to receive 35 the eye of a tag, and yielding means coöperating with said keeper to secure the tag.

4. A buckle comprising a frame having side members, strap-securing means between said side members, and a tag-attaching clip 40 comprising a keeper extending outwardly from one of said side members, said keeper having an end adapted to pass through the eye of a tag, and yielding means coöperating with said end of the keeper to secure the 45 tag.

5. A buckle comprising a frame having side members, strap-securing members between said side members, and a tag-attaching clip comprising a keeper in the form of 50 an eye extending outwardly from one of said side members, said eye having an end adapted to enter the eye of the tag, and a yielding spring tongue extending from the last mentioned side member and engaging 55 said end to secure the tag.

6. A tie of the character described provided with a buckle, and a tag-attaching clip secured to said buckle, said tag-attaching clip including a keeper extending from 60 said buckle to receive a portion of the tag, and yielding means whereby the tag is secured to said keeper.

In testimony that I claim the foregoing I hereunto affix my signature.

GEORGE R. THURMAN.
